Primary Examiner — Robin Webster(74) *Attorney, Agent, or Firm* — Birch, Stewart, Kolasch & Birch, LLP(57) **CLAIM**

The ornamental design for cleaning sheet, as shown and described.

DESCRIPTION

FIG. 1 is a front view of a cleaning sheet showing my new design;

FIG. 2 is a back view thereof;

FIG. 3 is a top view thereof;

FIG. 4 is a bottom view thereof;

FIG. 5 is a right side view thereof;

FIG. 6 is a left side view thereof;

FIG. 7 is a right, front perspective view thereof; and,

FIG. 8 is a reference view showing an example of the cleaning sheet that is in use with a cleaning sheet holder.

The broken lines illustrated in drawings form no part of the claimed design.
